UNITED STATES PATENT OFFICE.

ARCH K. WOOD, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A WATER-COOLER.

49,169.

Specification for Design.

Patented June 6, 1916.

Application filed February 3, 1916. Serial No. 76,060. Term of patent 7 years.

To all whom it may concern:

Be it known that I, ARCH K. WOOD, a citizen of the United States, and residing at Jeannette, in the county of Westmoreland, State of Pennsylvania, have invented a new, original, and ornamental Design for a Water-Cooler, of which the following is a specification, reference being had to the accompanying drawing, forming part thereof.

The figure is a perspective view of a water cooler, showing my new design.

I claim:

The ornamental design for a water cooler, as shown.

ARCH K. WOOD.
